(57) **CLAIM**

The ornamental design for a combined food and beverage storage container, as shown and described.

DESCRIPTION

FIG. 1 is a perspective view of a combined food and beverage storage container showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures depict portions that form no part of the claimed design. In FIG. 7, the area within the broken lines forms no part of the claimed design.

1 Claim, 5 Drawing Sheets
